CONTROL MECHANISM

Richard J. Jacker, Cincinnati, Ohio, assignor to
 The American Laundry Machinery Company,
 Cincinnati, Ohio, a corporation of Ohio

Application October 22, 1931, Serial No. 570,357

6 Claims. (Cl. 161—7)

My invention relates to automatic control mechanism for laundry and dry cleaning apparatus to control the performance of the several successive operations of the apparatus, thus eliminating the manual control of each operation. Hereinafter, the control will be described as being of the type operated by a constantly operating motor and as applied to a garment dry cleaning apparatus wherein a given formula is employed repeatedly, although different formulas are employed for garments of different texture or different colors and provision is made whereby the control mechanism can be quickly altered so as to control the apparatus for any particular formula. Also, provision is made whereby any portion of any formula can be omitted or can be repeated as desired, thus rendering the control flexible.

The dry cleaning apparatus illustrated is one similar to the apparatus disclosed in the application of Russell A. Hetzer, Ser. No. 462,061, filed June 18, 1930, to which reference may be had for details not herein disclosed, and comprises a motor driven revolving garment container within a treating compartment, a sump tank into which the treating liquid is permitted to drain from the treating compartment, a still and condenser wherein the treating liquid from the sump tank is reclaimed for further use, a storage tank in which the reclaimed treating liquid is stored for use in the treating compartment, a fan and air heater by means of which heated air is forced through the goods in the treating compartment for a drying operation, a condenser for removing treating medium from the air, and suitable valves or dampers by means of which the same fan forces fresh air through the goods in the treating compartment to deodorize the goods after the cleaning and drying operations. The control forming the subject matter of this application is designed to operate several valves, switches, and dampers at certain intervals to carry out any particular treating formula without any attention on the part of the operator after the apparatus is once placed in operation.

One embodiment of my invention is shown in the accompanying drawings wherein Fig. 1 is a rear elevation of a garment cleaning apparatus showing a control mechanism forming a part thereof; Fig. 2 is a view, partly in section and partly in elevation taken on the line 2—2 of Fig. 1; Fig. 3 is a plan view of the control mechanism constructed in accordance with my invention; Fig. 4 is a side elevation partly in section, of the

rewardmost side of the control shown in Fig. 3; Fig. 5 is a sectional view taken on the line 5—5 of Fig. 4; Figs. 6, 7, and 8 are detail views of the type of chain employed in the control mechanism; and Fig. 9 is a diagrammatic view showing the arrangement of valves and operating means therefor for controlling the flow of air in the drying and deodorizing circuit.

Referring to the drawings, the laundry apparatus shown comprises a fabric treating compartment 1 within which is mounted a rotatable goods containing cylinder disposed on a shaft 2 and driven by a motor 3 through suitable gearing 4, operation of the motor being controlled by a switch 5 normally spring pressed to closed position whereby the switch lever 6 must be operated to stop operation of the motor 3. In the operation of the apparatus, while the cylinder in the treating compartment 1 is rotating, having been filled with goods to be treated, a quantity of treating fluid is permitted to flow from a supply tank 7 into the treating compartment 1 through a pipe 8 under the control of a valve 9 normally held in closed position whereby it must be operated by moving the valve lever 10 to open the conduit between the storage tank and the treating compartment.

Then, after the goods in the treating compartment 1 have been subjected to the treating medium for a sufficient length of time, the used treating medium is drained from the compartment into a sump tank 11 through a pipe 12 under control of a valve 13 normally yieldingly held in closed position necessitating operation of the valve lever 14 to open the passage between the treating compartment and the sump tank. After this operation, the goods within the treating compartment are subjected to heated air forced through the compartment after having passed through an air heater 15 to which steam is supplied from a source of supply through a pipe 16 under the control of a valve 17 normally yieldingly held in closed position whereby the valve lever 18 must be operated to open the passage to permit steam to flow to the air heater.

From the treating compartment, the heated air passes through a condenser 19 kept cool by a constant flow of cold water through a pipe 20 under the control of a valve 21 normally yieldingly held in closed position whereby the valve lever 22 must be operated to open a passage for cold water to the condenser. The air is forced through the treating compartment 1 and condenser 19 by a fan 23 driven by a motor 24 whose operation is controlled by a switch 25 normally held in open

45

50

55

position whereby the switch lever 26 must be moved to bring about operation of the motor. Finally, to deodorize the goods within the treating compartment, fresh air is admitted into the compartment by opening a valve 27 in a conduit 28, this valve 27 being normally yieldingly held in closed position whereby a valve lever 29 must be operated to open the valve.

Operatively connected with the valve 27 and arranged to be moved in unison therewith are valves 30 and 31 in a circuit, including the treating compartment 1, condenser 19, fan 23, and air heater 15, in such manner that, when valve 27 is closed as shown, the valve 30 will close a passage to the atmosphere and the valve 31 will be in open position whereby heated air may be circulated through the treating compartment in a closed circuit. Reversely, when the valve 27 is open, the valve 30 is in open position and the valve 31 is closed whereby cold air will be drawn into the circuit past the valve 27 and then discharged to the atmosphere through the conduit 32. No automatic means is disclosed herein for controlling the operation of the stills 33 and 34 forming a part of the apparatus, the condenser 35, or the motor driven pump 36. Hence, these parts will not be described although they are shown to illustrate a complete garment cleaning apparatus and a control mechanism may be as readily applied thereto as to the other parts of the apparatus.

Substantially all of the parts forming the control mechanism constructed in accordance with my invention are supported or mounted on a suitable base 37 forming a part of or secured near the laundry apparatus with which it functions. In the present instance, the base 37 is secured below the air heater 15. Referring to Figs. 3 and 4, a roller 38 is disposed at the right hand end of the base 37, the shaft 39 of the roller being mounted in bearings provided in uprights 40 on the base 37. A small gear 41 is loosely mounted on one of the uprights 40 and is adapted to mesh with a large gear 42 on the shaft 39. The shaft and roller may be rotated by a crank handle 43 secured to the small gear 41.

At the left hand end of the base 37 a plurality of idlers 44 are mounted on shafts 45, these shafts being, in turn, mounted in suitable bearings provided in the opposed ends of suitable yokes 46 arranged to slide in horizontal ways 47 provided on vertical partitions 48 that are mounted on the base 37. A plurality of endless chains 49 are looped around the roller 38 at the right hand end and around the idlers 44 at the left hand end. That is, each chain is looped about a single idler 44 each of which is provided with a yoke 46 that is spring pressed to the left by means of a spring 50 and an adjusting screw 51 mounted in an adjustable bracket 52 whereby each chain 49 is held taut.

The particular garment cleaning apparatus is one in which seven separate levers or handles must be operated to bring about complete operation of the machine, namely, a cylinder motor switch lever, treating compartment fill lever, treating compartment drain lever, heater steam valve lever, condenser cold water valve lever, fan motor switch lever, and cold air valve lever. Therefore, each endless chain 49 employed to perform all the operations of a formula is provided with seven link divisions 53, and as many chains are provided as is desired to run different formulas. That is, one chain is provided for each formula. In the control illustrated, four endless

chains are provided, hence, four different formulas can be run.

Referring to Figs. 5 and 8, each link of each chain 49 is provided with seven spaced link divisions or slots 53 and each division or slot has a shoulder or off-set 54 in its rear end wall and a transversely extending pin 55 near its front end wall, the pin 55 extending entirely through a link and serving for all seven slots in that link, the slots being constructed for the purpose of securing detachable cam blocks 56 to the links.

Each cam block 56 is approximately as long as a link of the chain from pivot to pivot and slightly greater in width than one of the slots 53, the cam block being provided with a thinner extension which fits loosely into the slot 53 and having a shoulder or hook 57 thereon adapted to engage the shoulder 54 of the link and with a hook 58 adapted to engage the pin 55.

As clearly seen in Fig. 8, with this construction, the cam block 56 is locked against removal from the link as long as the shoulder and hook 57 and 58 engage the shoulder 54 and pin 55. A leaf spring 59 is secured to one end of the cam block extension that extends into the slot 53, this spring being adapted to bear against one end of the slot to yieldingly hold the cam block extension against the rearward end of the slot 53 with the shoulder 57 and hook 58 in engagement with the shoulder 54 and pin 55 respectively. Thus, any cam block can be secured in or removed from any desired slot 53 in any desired link of any chain 49.

A suitable driving means is provided for intermittently moving the chain 49 about the roller 38 and idler 44 apart from the hand crank 43 and connecting mechanism. Therefore, each longitudinal edge of each link of the separate chains 49 is provided with one or more ratchet teeth 60 which, as seen in Figs. 3 and 4, are adapted to be engaged by a gravity pawl 61 pivotally mounted as at 62 on the uppermost ends of supporting arms 63 which have their lower ends pivoted on a rod 64 secured in standards 65 on the base 37. The uppermost ends of the arms 63 are connected by means of rods 66 to crank pins 68 secured on each end of a shaft 67 that is driven through the medium of gearing 68 by a motor 67.

Constant rotation of the shaft 67 will move the arms 63 and pawl 61 forwardly and backwardly constantly to successively engage the ratchet teeth 60 on the links of the chain 49. A means is provided whereby the pawl 61 is held up out of engagement with the ratchet teeth 60 on the links of the chains 49 during the greater part of its forward and backward movements and in the particular control mechanism shown, the pawl 61 moves the chains 49 the distance of one link or one tooth each minute. That is, the parts are so synchronized that the shaft 67 makes one revolution every two seconds whereby the pawl 61 engages and moves the chains 49 the distance of one tooth 60 each thirty cycles of the movement of the shaft 67.

Ratchet lifting arms 63' are connected by a cross bar 68' whose lower beveled edge rests on a ratchet wheel 69 loosely mounted to rotate on the shaft 64. With this construction, as the pawl 61 is moved forwardly or to the right as shown in Fig. 4, the cross bar 68' takes into one tooth of the ratchet wheel 69 and rotates it clockwise the distance of one tooth, and when the pawl 61 moves backwardly the bar 68' slides over the next tooth on the ratchet wheel, the 75

wheel being prevented from moving contra-clockwise by a spring pawl 70 mounted on a cross member of the frame. The ratchet wheel 69 is provided, in this instance, with thirty teeth, one of which is a deep tooth 71 and when the cross bar 68' engages this deep tooth the ratchet lifting links 63' will drop a greater distance than when the other twenty-nine teeth are engaged by the bar 68' which will permit the pawl 61 to engage the teeth 60 of the chains 49. The lower ends of the links 63' are provided with forks 68" which straddle the shaft 64 and permit free vertical movement of the links 63'. Thus, the ratchet wheel 69 is given one complete rotation every minute and the chains 49 are moved along the distance of one tooth 60 every minute, the mechanism just described forming a timing means. It will be apparent that by varying the size of the ratchet wheel 69 and the number of teeth thereon, the speed of operation of the chains 49 and the time of operation of the various parts of the apparatus may be varied as desired.

To operatively connect the control mechanism previously described with the valve and switch control levers 6, 10, 14, 18, 22, 26, and 29 hereinbefore mentioned, a set of seven levers 72 are arranged above the four chains 49 to cooperate with the cam blocks 56 thereon. These levers 72 are loosely pivoted on a shaft 73 rigidly secured at each end in uprights 74 extending upwardly from the base 37 and have their short curved ends 75 so located that they will be lifted by the cam blocks 56 secured to the chains 49 when the chains are moved as described. When the short ends of the levers 72 are lifted by the cam blocks 56, the long end will be moved downwardly about the shaft 73 as a pivot and the extremity of the long end of each lever 72 is pivotally connected to the lowermost end of a flat pull rod 76 with the upper end of each pull rod 76 being connected to one of the valve and switch operating levers hereinbefore mentioned. That is, as seen in Figs. 1 and 2, the seven pull rods 76 are connected to operate the seven levers 6, 10, 14, 18, 22, 26, and 29. When any of the above levers are to be held in operated position for any given length of time, a successive row of cam blocks 56 mounted on the chain 49 will be presented to the short end of the lever 72. However, only the first block of the row will be provided with a beveled or inclined surface 77 to contact with the short end 75 of the lever 72.

As above described, in the control mechanism shown, provision is made on each chain 49 for seven longitudinal rows of cam blocks 56 so that one lever 72 cooperates with each row of blocks. Each chain 49 of the four chains shown represents a different formula and to change the operation of the machine from one formula to another the whole set of seven levers 72 are moved laterally on the shaft 73 to registering position with the particular chain 49 for causing operation of the apparatus in the desired formula, the pull rods 76 being of such length and flexibility that the proper operation of the parts is not affected by shifting the levers 72 from one side to the other.

To conveniently shift the set of seven levers 72 and accurately set them in registering position above the desired chain 49, I have provided a screw threaded shaft 78 above and parallel with the shaft 73, the shaft 78 having its bearings in the upper end of the uprights 74. A threaded nut 79 is mounted on the shaft 78 and is provided with a depending lug on each side of the seven

levers 72 so that the set of levers is snugly held between the depending lugs of the nut and necessarily travel along with said nut when the screw shaft 78 is turned. A crank handle 80 is provided on the shaft 78 for turning the shaft and the depending lugs on the nut 79 are preferably provided with holes through which the shaft 73 extends to give the shaft 73 additional support. 5

To raise and lower the upper lap of the chains 49 into and out of a position wherein they will 10 not be engaged by the pawl 61 and the short ends 75 of the levers 72 whereby the timing device may be rendered inoperative or may be moved forwardly or backwardly by rotation of the shaft 39 to set the control mechanism at any position 15 desired for any particular operation of the apparatus in any particular step of the formula, all four chains 49 are supported intermediate the roller 39 and idler 44 by a vertically movable shelf 81 guided by the ways 82 provided on the 20 uprights 74. The shelf 81 has two positions, the operative or up position as shown in Fig. 4, and the inoperative or down position. To raise and lower the shelf, two toggles 83, one adjacent either upright 74, are provided. The upper ends 25 of the toggles are pivotally connected as at 84 to the sub-structure of the shelf 81 and the lower ends of the toggles are rigidly connected to a rock shaft 85 having an operating lever 86 connected to one end thereof. Obviously, when the 30 shaft 85 is turned contra-clockwise the shelf 81 will be lowered whereby the upper lap of the chain 49 may move downwardly by gravity and, when the shaft is turned clockwise, the shelf 81 will be raised to move the upper lap of the 35 chains upwardly so that the teeth may be engaged by the bar 61 and the cam blocks 56 be engaged by the short ends 75 of the levers 72, the shelf being locked in its raised position by the toggle being moved past the dead center line 40 thereof. Thus, a means is provided for rendering the device inoperative or moving the upper laps of the chains 49 to such positions that they may be adjusted either forwardly or backwardly.

Referring to the drawings and the preceding 45 description, it will be seen that I have provided a device for controlling the operation of a laundry apparatus wherein the various steps of any formula will be automatically performed without the intervention of the operator after the 50 laundry apparatus and control mechanism are once started in operation. I have also provided a control mechanism wherein it is possible to vary the time that any of the steps of a formula are performed and wherein it is possible to adjust the control mechanism to bring about a repetition of the steps of the formula at any given point in the operation of the apparatus. Various other advantageous features will be readily apparent. 60

What I claim is:

1. Controlling mechanism of the character described, comprising a plurality of master control devices grouped together, each control device comprising an endless chain having a plurality 65 of control means arranged therealong, a plurality of control members for operation of apparatus, said control members being arranged to coact with said control means of one of said master control devices, means for driving said chains, 70 and means for selectively associating said control members with any one of said master control devices.

2. Controlling mechanism of the character described, comprising a plurality of master control 75

devices grouped together, each control device comprising an endless chain having a plurality of control means arranged in a predetermined relation therewith, a plurality of control members for operation of apparatus, said control members being arranged to coact with said control means of one of said master control devices, means for driving said chains in timed relation, and means operable at will for selectively associating said control members with any one of said master control devices.

3. Control mechanism of the character described, comprising a plurality of master control devices grouped together, each control device comprising an endless chain having a plurality of control means arranged therewith, a plurality of control members for operation of apparatus, said control members having flexible levers suspended with their ends adjacent the control devices in position to coact with said devices, and means for flexing said levers to position them to coact with any one of said master control devices.

4. The combination of claim 1, including means for relatively moving said chains and control members out of coacting position whereby the control devices may be set at any desired position of their operating cycle at the will of the operator.

5. Controlling mechanism for apparatus adapted to perform a series of operations in sequence, comprising a plurality of control members for operation of said apparatus, a plurality of master control devices grouped side by side, each control

device having a control means for each of said control members for coaction therewith, said control means being adjustably mounted on said device whereby the operation of said apparatus by one master control device may be varied and whereby various formulae for the operation of said apparatus may be set on said plural master control devices, means for driving said master control devices, and means for causing relative movement between said control members and said group of master control devices whereby said control members may be selectively operatively associated with any one of said master control devices.

6. Control mechanism for apparatus of the character described, comprising a plurality of control members for operation of said apparatus, a plurality of master control devices grouped together, each control device having a plurality of control means one for each of said control members for coaction therewith, said control means on each master control device being differently arranged providing various formulae for the operation of said apparatus on said plural master control devices, means for driving said master control devices, and means for causing relative movement between said control members and said group of master control devices whereby said control members may be selectively operatively associated with any one of said master control devices.

RICHARD J. JACKER.
